UNITED STATES PATENT OFFICE.

LEWIS D. ROBERTS, OF WASHINGTON, DISTRICT OF COLUMBIA.

CAN OPENER.

Application filed March 19, 1923. Serial No. 626,201.

To all whom it may concern:

Be it known that I, LEWIS D. ROBERTS, a citizen of the United States, residing at Washington, District of Columbia, have invented a new and useful Can Opener, of which the following is a specification.

This invention relates to can openers, one of its objects being to provide a device of this character adapted to be stamped out of sheet metal and the parts of which can be held together securely so as not to work loose when in use.

Another object is to provide a bearing or fulcrum wing at one end of the handle portion of the device, said wing being provided with an integral cap remover stamped from the metal of the handle portion.

Another object is to provide a sheet metal structure that is cheap to manufacture and requires the minimum number of operations for assembling.

With the foregoing and other objects in view which will appear as the description proceeds the invention consists of certain novel details of construction and combinations of parts which will be hereinafter more fully described and pointed out in the claims, it being understood that various changes may be made in the construction and arrangement of parts without departing from the spirit of the invention as claimed.

In the accompanying drawings the preferred form of the invention has been shown.

In said drawings:

Figure 1 is a side elevation of the can opener, the cork-screw being partly shifted to operative position.

Figure 2 is a plan view.

Figure 3 is a detail view of the cutting blade.

Figure 4 is an enlarged end elevation of the device.

Figure 5 is an enlarged section on line 5—5 Figure 1.

Figure 6 is an enlarged section on line 6—6 Figure 1.

Referring to the figures by characters of reference 1 designates a strip of sheet metal adapted to be shaped by means of dies so as to provide parallel side flanges 2 forming a longitudinal channel 3 therebetween extending a portion of the length of the strip. The flanges 2 gradually diverge away from the channel and cooperate with one end portion of the strip 1 to provide a grip portion 4 much broader than the channeled

portion and preferably slightly curved longitudinally. The preferred contour of this grip has been illustrated in Figures 1 and 2.

That end of the strip 1 remote from the grip 4 is bent to provide a transverse wing 5 lying in a plane perpendicular to the flanges 2. This wing has its transverse edge recessed longitudinally as shown at 6 to provide a fulcrum edge 7 which can be sufficiently sharp to bite into the surface on which it is bearing while the can opener is in use. The projecting portions 8 left at the ends of the edge 7 constitute guide lugs.

To facilitate the formation of the wing 5 it is necessary to provide a slot 9 along the intermediate or crown portion of the channel adjacent the wing. Otherwise it would not be practicable to bend the metal between dies and produce an article having the desired configuration. The formation of the slot allows those portions of the flanges adjacent the wing to bulge laterally as shown at 10, thereby to provide arcuate connecting portions between the top edges of the wing 5 and the parallel portions of the flanges 2.

For the purpose of saving the metal removed in the formation of the slot 9 said metal is utilized at a finger 11 which, during the bending of the wing 5 will be brought to upstanding position as shown in Figures 1 and 4. The free end of this finger is offset to form a lug 12 and a reinforcing rib 13 is pressed into this finger and extends longitudinally thereof from the lug 12 to the bearing or fulcrum edge 9 of wing 5.

It will be noted that the parts heretofore described are all stamped in one piece of metal and the cutting and bending of the metal can be effected in one operation.

The cutting blade, preferably formed of tool steel can be shaped as illustrated in Figures 1 and 3. It includes a head 14 having a straight top edge 15 and downwardly converging front and rear edges 16. The rear edge 16 merges into the rounded lower edge 17 of the blade. The front edge 16 extends to the back end of the cutting edge 18 of the blade and this cutting edge and the lower edge 17 converge to a point 19 as shown. The thickness of the blade is approximately the same as the distance between the flanges 2. Thus when the head 14 is inserted into the channel 3 it will

- frictionally engage the two flanges and the straight edge 15 will bear firmly against the intermediate or crown portion of the channel. The blade is held in place by means 5 of one or more rivets 20 extending transversely through the flanges 2. In the drawings a single rivet has been shown, it having been found in practice that where the straight edge 15 bears firmly against the 10 intermediate or crown portion of the channel a single rivet is all that is necessary to hold the blade fixedly against movement relative to the channel. Where one rivet is used it is preferred to locate it near the 15 front edge 16 of head 14 so that the greater portion of the length of the straight edge 15 will thrust against its bearing surface when the cutting blade is cutting through a can.
- 20 If desired a cork-screw 21 can be combined with the can opener, there being an eye 22 at one end of the cork-screw pivotally mounted on a rivet 23 secured in the flanges 2. When the cork-screw is not in 25 use it can be held against the concave face of the grip 4 where it will be kept out of contact with the hand of the user of the can opener.

In using this device a hole is punched 30 into a can by means of the point 19 of the cutting blade. The blade is then inserted into the hole thus produced and the fulcrum edge 7 is caused to rest on the margin of the can. By pulling upwardly on 35 the grip 4 the inner portion of the edge 18 will cut upwardly through the metal of the can and as the grip is moved downwardly following this operation the blade can be slipped forwardly so as to be brought to position to make another cut when the grip is 40 swung upwardly. During this action the edge 7 bites into the can to prevent the device from slipping.

It will be understood that by reversing 45 the can opener and placing the lug 12 under the edge of a bottle cap said cap can be removed readily.

It will be noted that the cutting blade lies in a plane intersecting and perpendicular to the wing 5 thus during the cutting 50 operation the thrust exerted through the blade is directly toward the wing.

By forming the arcuate bulged portions 10 the necessary clearance is provided above

the edge 18 to allow the blade to cut properly through the can. 55

What is claimed is:

1. In a device of the class described, a single strip of metal bent to provide a grip at one end, a transverse bearing wing at the other end, an intermediate channel, there being a slot in the intermediate wall of the channel extending up to the wing, those portions of the channel at the sides of the slot being bulged laterally and arched, a cutting blade having a head fitted snugly within the channel with one straight edge bearing throughout the length of the head against the intermediate wall of the channel, and a fastening means extending transversely through the channel and head. 70

2. In a device of the class described, a single strip of metal bent to provide a grip at one end, a transverse bearing wing at the other end, an intermediate channel, there being a slot in the intermediate wall of the channel extending up to the wing, those portions of the channel at the sides of the slot being bulged laterally and arched, a cutting blade having a head fitted snugly within the channel with one straight edge bearing throughout the length of the head against the intermediate wall of the channel, and a single fastening rivet extending transversely through the sides of the channel and the head of the blade at a point removed from the transverse center of the blade. 85

3. A device of the class described including a single strip of metal bent to provide a grip at one end, a transverse bearing wing at the other end, and an intermediate channel, there being a longitudinal slot in the strip between the wing and the channel, a finger at one end of the slot and having a terminal lug, a cutting blade having a head fitted snugly in the channel and a fastening device extending transversely through the channel and head, said blade having a cutting edge projecting past the wing. 90

In testimony that I claim the foregoing as my own, I have hereto affixed my signature in the presence of two witnesses.

LOUIS D. ROBERTS.
